US0D1102436S

(12) **United States Design Patent** (10) **Patent No.:** **US D1,102,436 S**
Cho et al. (45) **Date of Patent:** **** Nov. 18, 2025**

(54) **DISPLAY SCREEN OR PORTION THEREOF WITH GRAPHICAL USER INTERFACE**

(71) Applicant: **Lyft, Inc.**, San Francisco, CA (US)

(72) Inventors: **Kyong Tak Cho**, Santa Clara, CA (US); **David Walter Hildebrand**, Oakland, CA (US); **Young Kyo Kim**, San Francisco, CA (US); **Alison Frances Marlin**, Berkeley, CA (US); **Brian David Ng**, Santa Clara, CA (US); **Bomee Park**, Oakland, CA (US); **Suresh Pragada**, Dublin, CA (US); **Neil Pradip Shah**, San Carlos, CA (US)

(73) Assignee: **Lyft, Inc.**, San Francisco, CA (US)

(**) Term: **15 Years**

(21) Appl. No.: **29/729,735**

(22) Filed: **Mar. 30, 2020**

(51) LOC (15) Cl. **14-04**

(52) U.S. Cl.

USPC **D14/485**; D14/487

(58) **Field of Classification Search**

USPC D14/485-495

CPC G06F 3/048-04897

(57) **CLAIM**

The ornamental design for a display screen or portion thereof with graphical user interface as shown and described.

DESCRIPTION

FIGURE is a front view of a display screen or portion thereof with a graphical user interface showing our new design.

The outermost broken lines in the figure show a display screen or portion thereof and form no part of the claimed design. The remaining broken lines in the figure show portions of the graphical user interface that form no part of the claimed design.

1 Claim, 1 Drawing Sheet
